United States Patent Office

Des. 203,881
Patented Feb. 22, 1966

203,881

CONTOUR MEASURING PROJECTOR

James N. Burlin, New York, N.Y., and Henry Dreyfuss,
South Pasadena, Calif., assignors to Bausch & Lomb
Incorporated, Rochester, N.Y., a corporation of New
York

Filed Mar. 29, 1965, Ser. No. 84,468

Term of patent 14 years

(Cl. D57—1)

FIG. 1

FIG. 2

Des. 203,881

PAGE 5

FIG. 3

FIG. 4

FIG. 1 is a front perspective view of the left side of a contour measuring projector showing our new design;

FIG. 2 is a front perspective view of the right side of a contour measuring projector;

FIG. 3 is a rear perspective view on the aforesaid left side; and

FIG. 4 is a rear perspective view on the aforesaid right side of the contour measuring projector.

The essential features of our design are shown in full lines in the drawings.

We claim:

The ornamental design of a contour measuring projector, substantially as shown and described.
